UNITED STATES PATENT OFFICE.

MARCELLINE McCARTHY, OF NEW ORLEANS, LOUISIANA.

DESIGN FOR A CONDIMENT-SHAKER.

57,848.

Specification for Design.

Patented May 10, 1921.

Application filed October 9, 1920. Serial No. 415,916. Term of patent 7 years.

To all whom it may concern:

Be it known that I, MARCELLINE McCARTHY, a citizen of the United States, and resident of New Orleans, in the county of Orleans and State of Louisiana, have invented a new, original, and ornamental Design for Condiment-Shakers, (Case 1,) of which the following is a specification, reference being had to the accompanying drawing, forming a part thereof, in which—

Figure 1 is a plan view,
Fig. 2 is a side elevation, and
Fig. 3 is an end elevation.

I claim:

The ornamental design for a condiment shaker as shown.

MARCELLINE McCARTHY.
